DESIGN FOR A COSMETIC CASE

Philip A. Derham, Rosemont, and Jesse Herbert Newport, Jr., Overbrook Hills, Pa., assignors to The Waterbury Button Company, Waterbury, Conn., a corporation of Connecticut

Application May 9, 1941, Serial No. 100,862

Term of patent 7 years

To all whom it may concern:

Be it known that we, Philip A. Derham and Jesse Herbert Newport, Jr., citizens of the United States and residing at Rosemont and Overbrook Hills, respectively, county of Montgomery, State of Pennsylvania, have invented a new, original, and ornamental Design for Cosmetic Cases, of which the following is a specification, reference being had to the accompanying drawing, forming part thereof.

Fig. 1 is a top plan view of a cosmetic case, showing our new design.

Fig. 2 is a side view of the same.

Fig. 3 is a bottom plan view of the same.

Fig. 4 is a sectional view taken along the line 4—4 of Fig. 1, looking in the direction of the arrows.

We claim:

The ornamental design for a cosmetic case, as shown.
